UNITED STATES PATENT OFFICE

CARL M. PETERSEN, OF TRENTON, NEW JERSEY, ASSIGNOR TO CIRCLE F MFG. CO., OF TRENTON, NEW JERSEY, A CORPORATION OF NEW JERSEY

MULTIPLE-CONTROL SWITCH

Application filed July 3, 1928. Serial No. 290,178.

This invention relates to the subject of controller switches for electrical instruments and appliances, and more particularly to that class of switches for selectively controlling the heat supplied by a heating unit for various purposes, such as electric stoves, heating pads, motors, et cetera.

To that end a primary object of the invention contemplates a multiple control switch of the type referred to of simple construction, and reliable and positive in its action, while at the same time being easily and quickly changed from one set position to another. Also, a practical, and very desirable, object of the invention is to provide a controller switch construction which at all times will give a clear vision of the position of the switch, according to the selected heat desired.

With these and other objects in view which will be apparent to those familiar with the art without further description it will be understood that the invention consists in the novel construction, combination, and arrangement of parts hereinafter more fully described, illustrated and claimed. Though susceptible of structural modification without departure from the essentials of the invention a preferred and practical embodiment thereof is shown in the accompanying drawings, in which:—

Figure 1 is a front elevation of a fragment of the device, showing the operating handle and adjacent index.

Figure 2 is a front elevation of the device with the front cover removed.

Figure 3 is a side elevation, partly in section, exposing one of the individual switches.

Figure 4 is a top plan view of the device.

Figure 5 is a sectional view of the switch device taken on the line 5—5 of Fig. 2.

Figure 6 is a sectional view of the device taken on the line 6—6 of Fig. 3.

Figure 7 is a sectional view through the base of the device on the line 7—7 of Fig. 2.

Figure 8 is a sectional view through the insulation base of the device on the line 8—8 of Fig. 2.

Figure 9 is a rear elevation of the base of the device exposing a jumper or bridge strap

electrically connecting a pair of contact members.

Figure 10 is a perspective view of the oscillating switch plate unit of each of the separate or individual switches.

Figures 11, 12, 13 and 14 are diagrammatic views of the electrical circuit showing the arrangement of the individual switches respectively for the "off", "low", "medium" and "high" positions.

Like reference characters designate corresponding parts throughout the several figures of the drawings.

The novel switch device which constitutes the present invention may be arranged in any location or position, according to the particular electrical instrument or appliance with which it is associated, but for the purposes of this application it is sufficient to assume that the switch as an entirety is mounted in an upright position, as it would be for instance in connection with an electric stove unit. However, in any embodiment of the invention, or its use in connection with any particular apparatus or appliance, the device includes in its general organization an insulation base designated by the numeral 1, provided in one side thereof with a plurality of spaced switch chambers 1, 2 and 3 separated by the insulating walls 4 and 5 and respectively housing individual or separate switches which may conveniently be designated by the reference letters A, B and C respectively. These several switches are intended to be selected and operated consecutively for causing the heater unit of the apparatus or appliance to function "low", "medium", and "high", as well as "off".

The several individual switches or switch units A, B and C may be and preferably are similar in construction and action and a detailed description of one will suffice for the others. Accordingly, it will be seen from the illustration herein that each individual switch or switch unit, which is housed in one of the switch chambers in the base, preferably is of the toggle-movement type. This switch or switch movement includes as a principal part an oscillating operating yoke 6 having a swinging back and forth move-

ment within its enclosing switch chamber, and is of substantially U-shape form provided at the ends of its side arms 7 with the out-turned pivot pintles 8 having a free bearing in the bearing notches 9 formed in the outer edges of the side walls of the switch chamber. One of these pivot pintles 8 of the switch yoke 6 has rigidly fitted thereto, at its intermediate portion, the double bladed 10 switch blade member 10 having the oppositely extending separate blade members 11-11 which are intended respectively to engage and disengage at the same time the oppositely arranged fixed knife-contacts 12 and 13 15 which are mounted at one end and within the switch recess 1, and at one end and without the switch recess 1, respectively.

The snapping or throwing of the yoke and the switch blade member carried thereby, of 20 each switch unit, is accomplished through the intermediary of the coiled snapper spring 14, one end of which is held in position upon the holding lug or projection 15 in the cross-bar of the yoke 6 and the other end of which 25 spring is connected to the lever arm 16 provided at one end of the switch actuator or actuating yoke 17 which is pivotally mounted on a universal pivot rod 18 fitted at its ends in holding plates or equivalent supporting 30 members 19 at opposite ends or sides of the switch base 1.

The said switch actuator or yoke 17 is provided at its end opposite the lever arm 16 with a lever arm 20 also pivoted on the pivotal rod 18 and having a bearing fork or notch 21 adapted to be engaged by the rounded nose 22 of the cam finger 23 carried by a swinging dog 24 which in turn is carried by the operating member or lever 25 pivoted on 40 a supporting pivot 26 (see Figures 3 and 4). This operating member or lever 25 may conveniently project through the front cover plate 27 of the device and has fitted thereto a handle or finger grip 28 which plays in 45 front of an inductor index plate or dial 28a marked with the "off", "low", "medium" and "high" positions of the switch device.

It will now be observed from the description so far given, and referring particularly 50 to the separate switch or switch unit A that the operation of this switch for selected positions and "off" is caused by the movement of the operating member or lever 25 in either direction. The movement of the operating 55 member or lever is transmitted to the cam finger 23, the nose of which enters the bearing fork or notch 21 of the lever arm 20 of the actuator or yoke 17 (Fig. 4), resulting in the swinging of the said actuator or yoke 17 60 on its pivot thereby transmitting motion to its other lever arm 16 (Fig. 3) which in turn compresses the switch snapper-spring 14 and at the same time swings it within the switch yoke 6 past center of the latter. This movement results in snapping the double-bladed 65

switch-blade unit either into or out of engagement with the fixed knife-contacts 12 and 13, according to the direction in which the switch actuator or yoke 17 is thrown by the movement of the operating member or lever 25.

Referring to the separate switch or switch unit B the details of the switch proper are the same as the details of the switch proper or switch unit A already described, but in order 75 to distinguish these two switches as to the wiring it will be seen that this switch or switch unit B has two sets of fixed knife-contacts, the same being numbered respectively 30-31 and 32-33. Also, for the switch or 80 switch unit B the actuator or yoke therefor is designated 34. This switch actuator or yoke 34 is shorter than the switch actuator or yoke 17, but is mounted on the common pivot rod 18 and operates inside of the actuator or 85 yoke 17. Also, the forked or notched lever arm 35 at one end of the switch actuator 34 is engaged by a separate cam finger 36 carried by the swinging dog 24 and spaced from and set laterally out of the plane of the cam finger 23 for the switch actuator 17, so that the actuator 34 is operated independently of and consecutively with the actuator 17. The other lever arm 37 of the actuator 34 connects with the snapper spring of the individual switch or switch unit B, in the same manner, as 90 shown in Fig. 5.

The third individual switch or switch unit C likewise has its own switch actuator or yoke 38 pivoted on the common pivot rod 18 having at one end the forked or notched lever arm 39 which is engaged by the separate cam finger 40 carried by the swinging dog 24 but spaced from and set laterally out of line 100 with the cam fingers 23 and 36 respectively 105 for the actuator 17 and 34. The other lever arm 41 of the switch actuator or yoke 38 connects with the switch snapper spring in the manner shown in Fig. 5.

Thus, it will be seen that on account of the spaced and the laterally out-of-line stepped relation of the cam fingers 23, 36 and 40 a movement of the operating member or lever 25 in one direction, through the extent of that movement, will respectively and consecutively bring the switches A, B and C into action in order that the switch device may function "low", "medium" or "high". A single movement of the operating member or lever 25 in the opposite direction will consecutively operate the separate switches from "high", "medium" and "low", or from any of these positions, back to the "off" position.

Now, in order further to visualize and explain the function of the multiple controller switch device reference now is made to the diagrammatic illustrations of Figs. 11, 12, 13 and 14 wherein the individual switches or switch units are designated respectively as 125 before, A, B and C and the fixed knife-con-

tacts are designated as given in Figs. 2, 7 and 8 respectively 12, 13, 30—31, 32—33, 12^a and 13^a. The double arrangement of contacts 30—31 and 32—33 are the knife-contacts associated with the intermediate switch or 5 switch unit B, and the knife-contacts 12—13 and 12^a—13^a are respectively parts of the separate switches or switch units A and C. It will also be seen from this diagram that the contacts 12 and 12^a of the switches A and B 10 are directly connected by the jumper or bridge strap 42, and that the contacts 32—33 are connected with the same binding post 43 and that the contacts 13^a and 31 respectively 15 of the switches B and C are united and connected with a common binding post 44. The heater unit designated by the reference letter H preferably is divided into two coils or parts a and b each of which separately is adapted 20 to, and has the capacity for, taking the full voltage. Therefore, it will be seen that on the "low" position the heater unit H has double the resistance actually necessary and will therefore produce a very low heat.

25 The various positions of the switches for the several positions of the controller device are clearly shown in the diagrams of Figs. 11, 12, 13 and 14. In Fig. 11 there is shown the relative positions of the switches when the operating handle indicates the "off" position and in Fig. 12 the switch A is closed and the switch B is also closed so that the relative arrangement of switches A and B are such that the entire heating unit is used as the 30 resistance, thereby giving a low heat. Referring to Fig. 13 it will be observed that the second switch B is shown thrown over in the opposite direction to the "medium" position, and at this point only one-half of the 35 heating unit is working but at its full capacity. Referring to Fig. 14 the third switch C is shown in operation and in this position the handle member is at the "high" location and in such position both the parts a and b 40 of the heater unit are working on a full voltage. Of course when the operating handle is moved from "high" to "off" the above actions are merely reversed.

45 From the foregoing it is thought that the construction, operation and advantages of the herein described multiple controller switch device will be readily apparent without further description and it will also be understood that changes in the form, proportion and minor details of construction may be modified or changed without departing from the essential features and scope of the invention.

I claim:—

50 1. An electrical control switch including a plurality of separate switch units, a plurality of switch actuators having a nested relation and each operatively connecting with one of the switch units to actuate the same, 55 and a single operating means for independ-

ently and consecutively operating the switch actuators.

2. An electrical control switch including a plurality of separate switch units, a plurality of switch actuators having a nested relation and each operatively connecting with one of the switch units to actuate the same, and a single operating means for independently and consecutively operating the switch actuators in either direction. 70

3. An electrical control switch including a base, a plurality of separate switch units carried by the base, a plurality of swinging switch actuators arranged in nested relation and of different lengths, each said actuator having an operative connection with one of the switch units, and a single operating member adapted to have an operating engagement consecutively with the switch actuators. 75

4. An electrical control switch including a base, a plurality of switch units, a plurality of nesting switch actuators pivotally supported and operatively connected at one end with one of the switch units and each provided at its other end with a forked element, 80 and a common operating member carrying an operating dog having an independent but progressive operating engagement with the forked elements of the several switch units. 85

5. An electrical control switch including a base, a plurality of separate snap-switch units, a plurality of switch actuating yokes pivotally supported over the base and arranged in nested relation, each of said yokes having an operating connection at one end 90 with one of the snap-switch units and at its other end with a forked element, and an operating lever carrying a swinging dog provided with a plurality of spaced and laterally stepped cam-fingers which separately 100 and consecutively engage the forked elements 105 of the switch actuating yokes.

6. An electrical control switch including a base provided with a plurality of separate switch chambers, a snap-switch unit associated with each switch chamber and including spaced knife contacts and a spring-thrown switch-blade unit, a plurality of switch actuators arranged in nested relation and each having an operating connection with one of the snap-switches, and a common operating means having a progressive and consecutive operating engagement with the separate switch actuators for moving the same consecutively in either direction. 115

7. An electrical control device comprising a plurality of switches, a plurality of nested switch actuators individual, respectively, to said switches, and means for operating said actuators. 120

8. An electrical control device comprising a plurality of switches, a plurality of nested switch actuators individual, respectively, to said switches, and a single operating means 130

for said actuators effective to actuate the latter individually.

9. An electrical control device comprising a plurality of switches, a plurality of rotatable switch actuators individual, respectively, to said switches and having a common axis of rotation and being inclusive of operator engaging portions disposed in different planes spaced longitudinally with respect to 10 the axis of rotation of said actuators, and an operator having means for successive engagement with said portions during continuous movement of the actuator.

10. An electrical control device comprising 15 a plurality of switches, a plurality of switch actuators individual, respectively, to said switches, and a rotatable operator for said actuators having actuator engaging portions disposed in different planes spaced longitudinally with respect to the axis of rotation of said operator and adapted for individual successive engagement with said actuators respectively during continuous movement of said operator.

25 11. An electrical control device comprising a plurality of switches, a plurality of rotatable switch actuators having a common axis of rotation and extending in radial spaced overlying relation with respect to one another, and means for operating said actuators.

30 12. An electrical control device comprising a plurality of switches, a plurality of rotatable switch actuators having a common axis of rotation and extending in radial spaced 35 overlying relation with respect to one another, and a single means for successively operating said actuators during continuous movement of said means in a single direction.

30 In testimony whereof I hereunto affix my
40 signature.

CARL M. PETERSEN.
